MAIL BOX AND LIGHTING FIXTURE

Filed May 2, 1923

E. H. Loftin

UNITED STATES PATENT OFFICE.

EDWARD H. LOFTIN, OF WASHINGTON, DISTRICT OF COLUMBIA.

MAIL BOX AND LIGHTING FIXTURE.

Application filed May 2, 1923. Serial No. 636,234.

My invention resides in combining a mail box and a lighting fixture in one device or structure, thereby resulting in an economy in material, preservation of the appearance 5 of the premises where employed, as well as other readily apparent advantages.

Figure 1 is a front view of the invention in one of its forms,

Figure 2 is a side view in section of Figure 1,

Figure 3 is a front view of the invention in a second form, and

Figure 4 a side view in section of Figure 3.

Referring to Figures 1 and 2, 1 is a mail box having a wall of glass or transparent material parts 2, held in place by metal or other non-fragile material framework 3; the top of the box having a slot 4 suitable for 15 inserting letters and other mail matter; the front of the box has a hinged door 5 suitable for withdrawing mail matter, which door may be provided with a suitable lock or catch. The box has a space 6 of suitable 20 size for receiving mail matter. The box has a backing 7, preferably of metallic framework, provided with a recess 8 in which is set a lamp socket 9 for lamp 10. Holes 11 provide for ventilation to carry off heat of 25 lamp 10. Screws 12 hold the structure in place on its supporting structure 13, which may be the side wall of a house. The wires 30 14 carry the electrical current for the lamp 10. The holes 15 give access to the screws 12.

Referring to Figures 3 and 4, 1 is a mail box, which may be a metallic casting, having a bracket 16 for supporting a lamp, a slot 4 for inserting mail matter and a hinged

door 5 for withdrawing mail matter. A 40 lamp socket 9 is secured at the top of the bracket 16, and receives lamp 10. A protective globe 17 may be secured in place by the screws 18. The wires 14 carry current for the lamp 10. The structure is secured to its 45 support 13, which may be the wall of a house, by the screws 12 reached through the door 5.

It will thus be seen that I have provided a structure admirably adapted to house mail 50 matter and at the same time support and protect a source of efficient illumination, as well as housing the necessary fittings and wires for said source. Such an arrangement permits of the use of a single structure 55 for the dual purpose at the fronts of residences, thereby preserving their appearance in addition to the resulting economy in material and cost.

Having described my invention, I claim:

1. A mail box and lighting fixture combined in one structure comprising a bracket, means for securing said bracket to a support, a mail space within said bracket, a source of electrical illumination carried by 65 said bracket so as to permit general illumination from said source exteriorly of said mail space.

2. A mail box and lighting fixture combined in one structure comprising a bracket 70 having an enlarged hollow portion securable to a support and an upstanding projecting portion for supporting a source of illumination, means for entering and means for removing mail matter from said enlarged hollow portion, and means for securing said bracket to a support.

EDWARD H. LOFTIN.
